UNITED STATES PATENT OFFICE.

ARTHUR W. LYDA, OF NEW BERLIN, OHIO.

SHADE AND CURTAIN FIXTURE.

1,128,016.

Specification of Letters Patent.

Patented Feb. 9, 1915.

Application filed March 21, 1914. Serial No. 826,283.

To all whom it may concern:

Be it known that I, ARTHUR W. LYDA, a citizen of the United States, residing at New Berlin, in the county of Stark and State of Ohio, have invented a new and useful Shade and Curtain Fixture, of which the following is a specification.

This invention relates to improvements in shades and curtain fixtures.

10 An object of the present invention is to provide a fixture which may be easily and quickly secured to a window for the supporting of curtain rods, curtain poles and shade rollers.

15 A further object is to provide telescoping supports which rigidly engage the finish of a window frame and to which supports are detachably secured upstanding brackets for the support of the curtain poles and rods and shade rollers.

20 A further object is to provide telescoping supports which may be secured to finish of different size and which supports include an outstanding bracket for the support of a shade roller.

25 A further object is to provide telescoping supports which engage a window finish and to which are detachably and adjustably secured upstanding brackets for the support of curtain rods or poles or shade rollers, as the case may be.

30 A further object is to provide shade and curtain fixtures which may be raised or lowered while the curtains are supported therebetween so that the shades and curtains will be hung in a substantially horizontal manner and may be adjusted toward or away from the upper extremity of the window.

35 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

40 In the drawings accompanying this specification and forming a part thereof, the preferred embodiment of my invention has been illustrated, in which:—

45 Figure 1 is a view in perspective of a portion of a window with my improved

shade and curtain fixtures attached thereto. Fig. 2 is a detail view in perspective of one form of the telescoping supports with an upstanding bracket affixed thereto. Fig. 3 is a longitudinal view in section of the foregoing, showing the manner in which the telescoping supports engage the finish of the window. Fig. 4 is a bottom plan view of the telescoping supports. Fig. 5 is a front view in elevation of a second form of telescoping support. Fig. 6 is a top plan view thereof in section. Fig. 7 is a fragmental view, illustrating the threaded connection between one of the brackets and the socket terminated arm.

50 Referring to the drawings in which similar reference numerals designate corresponding parts throughout the several views, 7 represents the finish of a window frame and to which my improved shade and curtain fixtures are secured. However, it is to be noted that the structure herein disclosed may be attached to the frame of passageways or similar places for the support of portières or curtains.

55 The telescoping supports as illustrated in Figs. 2, 3 and 4 include the main supporting member 8 and the secondary supporting member 9, which is slidably mounted therein. The supports 8 and 9 are polygonal in cross section, thus holding the same against relative rotation. Extending longitudinally of the main supporting member 8 is the draw bolt 10, the head 11 of which projects beyond the end wall 12 of the main supporting member and provides a wrench engageable surface for the rotation of the bolt.

60 The auxiliary supporting member 9 is provided with the open end 13 through which the bolt 10 extends and adjacent which end are the outstanding ears 14 receiving a nut 15 therebetween and holding the same against rotation. The bolt 10 extends through and threadedly engages the nut and is thus adapted to advance and retract the auxiliary supporting member. Thus the supporting members may be forcibly telescoped to thus bring the outstanding ledges 16 and 17 with which they are provided, into forced contact with the finish 65 which lies therebetween.

70 The auxiliary supporting or clamping member is provided with the longitudinally extending slot 19 which receives the shank of the locking member 20. The latter ex-

tends through the aperture 21 in the main supporting or clamping member, being rotatably retained thereby, and is provided with the head 22 which prevents the accidental displacement or detachment thereof.

The outstanding ledge 16 of the main supporting or clamping member is provided with the annular plate 23 which receives, and supports one of the shade rollers therein. The telescoping supports are made as right and left's so that they may be attached to the opposite sides of a window to support a shade roller therebetween. A somewhat modified form of auxiliary supporting or 15 clamping member is illustrated in Figs. 5 and 6, in which figures, the outstanding ledge 17 has been replaced by the foot 24 through which a securing screw or bolt 25 extends and which form is used in those 20 cases in which it is not practical to engage the side edges of the finish between the two outstanding ledges. This may be due to the fact that the finish is such that it prevents the clamping arms from contacting with 25 both side edges at the same time, or that the finish is of such width as to render the same impractical.

In order to support either one or more shade rollers the upstanding brackets 26 are 30 provided and are formed with the slots 27 which receives the head 28 of the locking member 20 therethrough and which locking member when turned to bring the head transversely of the slot, securely locks the 35 bracket to the supporting and clamping members. The upstanding bracket is provided with the spaced arms 29 which carry the shade roller or curtain pole receiving sockets 30. The number of arms 29 will 40 depend upon the number of shades to be supported as will be readily appreciated. The bracket in Fig. 5 includes a single arm whereas the bracket illustrated in Fig. 2 is provided with two arms. Such changes 45 however, come clearly within the scope of the invention.

The bracket 31 illustrated in Fig. 1, has its outermost end offset as at 32, and to 50 which offset portion is rigidly secured the standard 33, to which latter is secured the curtain pole supporting arm 34. The upstanding arm or standard 33 can be removed from the bracket 31 and one of the arms 29 with its socket 30 inserted in lieu thereof. 55 This change can be readily effected by providing an aperture through which a bolt 35 extends with a thread corresponding to the thread with which one of the arms 29 is provided, such as illustrated in Fig. 7. The 60 fixtures in Fig. 1 are right and left handed and illustrate the manner in which the right and left-hand fixtures can be arranged upon a window, so that one will not interfere with the other for the support of the curtain rods, curtain poles and shade rollers.

Having thus fully described my invention, what I claim is:—

1. A device of the class described, comprising telescoping clamping members, means for forcibly telescoping the same, a bracket adjustably secured to said clamping members, and a plurality of outstanding arms carried by said bracket and provided with offset socketed ends, said sockets positioned one beyond the other and lying in substantially a horizontal plane. 75

2. A device of the class described, comprising telescoping clamping members, means for forcibly telescoping the same, a bracket adjustably and detachably secured to and carried by said telescoping members, said bracket provided with a threaded aperture extending therein, and a socket terminated arm provided with an offset threaded end adapted to detachably engage the 80 threaded aperture of the bracket. 85

3. In a device of the class described, a main supporting member provided with an open end and a threaded bolt extending longitudinally thereof and with an outstanding ledge projecting therefrom, a secondary supporting member non-rotatably telescoping within the first mentioned supporting member and provided with an open end, the secondary supporting member provided at 90 adjacent ends with outstanding ears, a nut non-rotatably and non-shiftably secured between said ears and threadedly engaging said bolt, said secondary member provided with an offset ledge acting in conjunction 95 with the first named ledge to form a pair 100 of clamps, and a bracket adjustably secured to said supporting members and provided with means for securing a curtain pole thereto. 105

4. In a device of the class described, a main supporting member provided with an open end and a threaded bolt extending longitudinally thereof and with an outstanding ledge projecting therefrom, a secondary supporting member non-rotatably telescoping within the first mentioned supporting member and provided with an open end, the secondary supporting member provided at 110 adjacent ends with outstanding ears, a nut non-rotatably and non-shiftably secured between said ears and threadedly engaging said bolt, said secondary supporting member provided with an offset ledge acting in conjunction with the first named 115 ledge to form a pair of clamps, said main supporting member provided with an aperture extending therethrough, registering with a slot in the secondary supporting member, a locking member rotatably disposed within said aperture and slot and projecting therebeyond, a bracket adjustably and detachably engaged by said locking member, said bracket provided with means for securing a curtain pole thereto. 120 125 130

5. A device of the class described, comprising a supporting member, a bracket adjustably secured thereto, and a plurality of outstanding arms carried by said bracket and provided with offset coextensive socketed ends.

In testimony that I claim the foregoing as

my own, I have hereto affixed my signature in the presence of two witnesses.

ARTHUR W. LYDA.
